UNITED STATES PATENT OFFICE.

FRIEDRICH WILHELM BUDIG, OF FALKENBERG-GRUNAU, NEAR BERLIN, GERMANY.

FLYING MACHINE.

1,419,447.

Specification of Letters Patent. Patented June 13, 1922.

Application filed June 16, 1921. Serial No. 476,125.

To all whom it may concern:

Be it known that I, FRIEDRICH WILHELM BUDIG, citizen of the State of Prussia, residing at Falkenberg-Grunau, near Berlin, in the State of Prussia, Germany, have invented certain new and useful Improvements in Flying Machines (for which I have filed applications in France Aug. 1, 1914, and in Germany Jan. 29, 1920, and Nov. 20, 1920), 10 of which the following is a specification.

This invention relates to a steadyng device. It consists in the combination of the supporting planes proper with an automatically adjustable steadyng plane. This latter plane is rotatably supported upon an axle supported in its turn by the flying machine, and it forms, together with an immovable surface with which it is connected, preferably by bellows, a hollow space within 20 in which a depression may be produced in known manner by the mediation of a feeler surface. The steadyng plane is adjusted to various inclinations by that depression, contrary to the action of a spring. Besides 25 these arrangements, other ones also forming parts of the present invention relate to means for correctly adjusting the steadyng plane, as is particularly necessary for soaring flying apparatus.

Referring to the accompanying drawing, Figure 1 is a vertical section through a motorless flying machine provided with the novel device in question, this latter being shown in the position it occupies at too slow 35 flight; Figure 2 is a side-view of the machine, only some upper parts (2, 5, 14) and a lower part (9) being shown in section, and the position of the automatic steadyng device being that which it occupies at normal speed; Figure 3 is a diagrammatical 40 illustration of the succession of the swing motions of the machine if flying in soaring manner; and Figure 4 is a side-view of a soaring flying machine having a small auxiliary motor.

The upper body 2 of the steadyng plane is hinged to a horizontal axle 1 firmly supported by the frame of the flying machine. Affixed to said body 2 is a counterpoise 3, 50 the arrangement being such that the total centre of gravity of the poise and the body 2 is located above the common axis of rotation so that in the case of changes of the speed of the flying machine the law of inertia initiates a favorable swinging or turn 55 of the upper body 2.

Parallel with the body 2, and having the same breadth as this body, is an immovable plate 4, to the rear edge of which is hinged the horizontal rudder 5 for altitude steering. The body 2 and the plate 4 are connected with each other by bellows 6 forming or enclosing a chamber 7 which communicates by a channel or passage 8 with the hollow feeler plane 9 which has the 65 shape of an inverted supporting plane and is provided with a slot 10 extending over the whole of its breadth. 11 is a spring which tends to turn the body upwards around the axle 1, that is to say, to expand 70 the bellows. The position of the parts 2 and 6, if no partial vacuum within the bellows counteracts the spring, is that shown in Figure 1.

The bellows communicates with the atmosphere not only through the channel 8, but also through an aperture 12 which is at the front of the machine and constantly open. The sectional area of the aperture 12 is smaller than that of the slot 10. The 75 supply of air through the aperture 12 does not materially affect the degree of rarefaction in the bellows as long as the air entering through that aperture flows off through said slot, as is the case during flying with 80 normal speed. But if the speed decreases, the body 2 can rise, under the pressure of the spring 11, far more quickly than would be the case if no supply of air through the 85 aperture 12 would take place, because, as is known by experience, air, even at a reduced speed, can enter only with great difficulty through the slot 10 into the bellows.

In order to accelerate the swinging movement of the body 2 in the direction to the 95 plate 4 at an increase of the speed of flight, the space 7 is connected by one or more air-channels 13 provided in rigid parts of the structure preferably tubes, and forming a kind of girder with the spaces of hollow 100 bodies 14 united with the main supporting planes. The tubes 13, or their equivalents, carry the above described combination and arrangement of parts and serve also for fastening the means provided for the landing. The hollow body 14 forms a rigid piece for and of the supporting plane and its front portion the blowing-at edge of said plane. The supporting wall of that body 14 differs from an ordinary hollow supporting plane chiefly by a slot 15 which is provided in the lower surface of the projecting 105 110

front part of the body 14, similarly to the additional resistance, in consequence of slot 10, and the length of which is about one fourth of the length of the slot 10, provided, that the machine has an aperture such as 12.

- 5 By measurements it is known that at that place of the supporting frame profile where the slot 15 is located a strong depression is produced at quick flight. This observation confirms that at slow flight the slot 15 assists 10 the action of the aperture 12, and at quick flight assists the action of the slot 10. Thus, if the angle of incidence at which the flight takes place is reduced, then, by the addition of the slot length 15 with the slot length 15 15 20 25 30 35 40 45 50 55 60 65 70 75 80 85 90 95 100 105 110 115 120 125 130
- The manner in which the body 2 is turned in the one or the other direction will become clear from a description dealing with flying in soaring manner, as follows:

- 25 Supposing the machine be soaring motionless in a constant head-wind under a large angle of incidence. In this case the lifting power R acts at the main supporting plane, and the lifting power X acts at the 30 steadyng surface. The lifting power of the horizontal rudder 5 which latter is controlled by the hand of the pilot, and the buoyancy of the stationary plate 4 may be neglected in these considerations because said two influences 35 approximately compensate the downwardly directed power of the receptacle 9. Besides the lifting power X , also the power of the spring 11 acts upon the body 2, in the same direction as said power X , 40 and, furthermore, also the suction power Z which is produced in the space 7 by the depression and acts in the opposite direction. These three powers balance each other at normal flight and determine the profile of 45 the steadyng surface, as illustrated in Figure 2.

Now, if the wind relatively to the flying machine, suddenly grows stronger owing to a squall or gust, then also the powers X 50 and R increase at the same time. Although also the suction power at the slot 10 becomes greater at the same time, still, the power Z does not immediately vary because the amount of air to be led away is increased by the supply of air taking place 55 through the apertures 12 and 15.

Besides, the increased suction power at the slot 10 which tends to increase the power Z is opposed by three other powers. Firstly, 60 the increased lifting power X tends to turn the body 2 upwards which is made possible only by air entering through the apertures 12 and 15. Secondly, the flying machine is, at the commencement of the squall or gust, 65 at first shoved backward by reason of the

which the high-lying center of gravity of the body 2 and the poise 3 swing forward by reason of their inertia; thirdly, this latter cause makes the air present within the channel 13 move in the direction to the space 7.

A sudden increase of the lifting power X by an outer wind power causes, thus, the body 2 to swing upwards, whereby the additional buoyancy at the front of the machine is made ineffective.

Matters are different with the rigid main supporting surface at which the power R has been increased. The diagram of forces (Figure 3) shows that the front of the machine has remained at the point C, owing to the annihilation of the addition to the power X , whereas the main supporting plane ascends from A to B. The swinging motion in forward direction occurring at the rear part of the machine being lifted entails forward drive, whereby the speed of the machine is increased and, also a variation in the play of forces at the steadyng devicer is brought about.

As the angle of incidence at the main supporting plane has become smaller by reason of the additional upward motion, suction takes place at the slot 15, and as also the opposing forces that acted upon the body 2 do no more exist, this latter is turned in the direction of the plate 4 whereby the buoyancy at the front of the machine is increased and this latter rises from the position C to the position D.

From both successively occurring motions of the flying machine results that this latter is rising for the height H without a loss of speed.

In the practical application of the arrangement in question a greater measure than the length C—A which is chosen only by way of example will be given the radius of oscillation; that may be easily attained by only partially annihilating, by the means stated, the power increased by the squall or gust.

Owing to its dimension, the rear rim of the movable body 2 forms for the pilot a readily visible indicator of the conditions of motions of the flying machine. The pilot may at his discretion either promote the indications of the rear rim or edge of the body 2 by appropriately operating the horizontal rudder or oppose them, also by appropriately actuating said rudder, for instance at landing.

The flying machines with but slight load per unit of surface are easily overturned by wind after the landing. The soaring flying machines shown in Figure 4 is so constructed that the wind cannot lift its front part off the ground because an aperture is provided which is kept closed during the flight by a flap 16, but permits of a large supply

of air through the channel 17 if it is open, so that the steadyng plane is ensured against being drawn against the plate 4.

Having now described my invention, what I desire to secure by a patent of the United States is:

1. A flying machine, comprising, in combination, a steadyng body adapted to swing around a horizontal axis; a horizontal axle forming said axis and being supported by the flying machine; a stationary plate arranged behind and below said body; pliable means connecting said plate and the said body and forming a hollow space together with them; and means for producing a depression within said space.

2. A flying machine, comprising, in combination, a steadyng body adapted to swing around a horizontal axis; a horizontal axle forming said axis and being supported by the flying machine; bellows arranged behind and below said body and connecting it with the flying machine; and means for producing a depression within said bellows.

3. A flying machine, comprising, in combination, a steadyng body adapted to swing around a horizontal axis; a horizontal axle forming said axis and being supported by the flying machine; a stationary plate arranged behind and below said body; pliable means connecting said plate and the said body and forming a hollow space together with them; means for producing a depression within said space; and an aperture through which the said space constantly communicates with the atmosphere.

4. A flying machine, comprising, in combination, a steadyng body adapted to swing around a horizontal axis; a horizontal axle forming said axis and being supported by the flying machine; bellows arranged behind and below said body and connecting it with the flying machine; means for producing a depression within said bellows; and an aperture through which the said bellows constantly communicate with the atmosphere.

5. A flying machine, comprising, in combination, a steadyng body adapted to swing around a horizontal axis; a horizontal axle forming said axis and being supported by the flying machine; a stationary plate arranged behind and below said body; pliable means connecting said plate and the said body and forming a hollow space together with them; an aperture through which the said space constantly communicates with the atmosphere and air receptacles arranged behind said space and communicating with it and extending in the longitudinal direction of the machine.

6. A flying machine, comprising, in combination, a steadyng body adapted to swing around a horizontal axis; a horizontal axle forming said axis and being supported by

the flying machine; bellows arranged behind and below said body and connecting it with the flying machine; means for producing a depression within said bellows; an aperture through which the said bellows constantly communicate with the atmosphere; and air receptacles arranged behind said space and communicating with it and extending in the longitudinal direction of the machine.

7. A flying machine, comprising, in combination, a steadyng body adapted to swing around a horizontal axis; a horizontal axle forming said axis and being supported by the flying machine; a stationary plate arranged behind and below said body; pliable means connecting said plate and the said body and forming a hollow space together with them; means for producing a depression within said space; and a counterpoise so arranged as to have the common center of gravity of the said body and said counterpoise lie vertically above said axle.

8. A flying machine, comprising, in combination, a steadyng body adapted to swing around a horizontal axis; a horizontal axle forming said axis and being supported by the flying machine; bellows arranged behind and below said body and connecting it with the flying machine; means for producing a depression within said bellows; and a counterpoise so arranged as to have the common center of gravity of the said body and said counterpoise lie vertically above said axle.

9. A flying machine, comprising, in combination, a steadyng body adapted to swing around a horizontal axis; a horizontal axle forming said axis and being supported by the flying machine; a stationary plate arranged behind and below said body; pliable means connecting said plate and the said body and forming a hollow space together with them; and two differently shaped hollow bodies, of which the one is located below the said body and the other behind it, substantially as described and shown.

10. A flying machine, comprising, in combination, a steadyng body adapted to swing around a horizontal axis; a horizontal axle forming said axis and being supported by the flying machine; bellows arranged behind and below said body and connecting it with the flying machine; and two differently shaped hollow bodies, of which the one is located below the said body and the other behind it, substantially as described and shown.

In testimony whereof I have affixed my signature in presence of two witnesses.
